UNITED STATES PATENT OFFICE

2,499,783

COUNTER MOLDER

Jean H. Scharffenberg, Lynn, Mass., assignor to
 Stewart Bros., Inc., Lynn, Mass., a corporation
 of Massachusetts

Application July 27, 1948, Serial No. 40,853

7 Claims. (Cl. 12—66)

1

This invention relates to machines for molding counter blanks and consists in improved wiper mechanism cooperating with improved molds for molding the marginal portions of a counter blank to form a flat heel seat flange and simultaneously to form depending flanges in that part of the margin of the counter which extends into the shank of a fully constructed shoe.

In general, counter molding machines are equipped with a center mold or plug resembling the heel and shank portions of a shoe last and cooperating side molds shaped to engage the body of the blank and impart a permanent curvature thereto. The counter blanks are placed in the molds so that when the molds are closed, the marginal portions of the counter projects outwardly from the face of the molds. A flange plate is then advanced to engage the protruding margin of the blank, and wipe it forward and inwardly upon the face of the center mold, thus forming a horseshoe shaped flange which is subsequently used for attaching the molded counter to the shoe bottom.

Preformed counters made in this manner with only a flat heel seat flange can be used readily in McKay sewn shoes, and three-sole stitch-down shoes, but when incorporated into a welt sewn shoe of the Goodyear type there are certain limiting features. Either the counter must be made short enough so that when it is laid over the heel area of the insole the heel seat flange does not overlap the rib of the insole. Or if it is desired to use a longer counter, the heel seat flange must be cut away to allow the forward corners of the counter to extend along the shank outside the insole rib. Or finally, a third possibility is to bend the heel seat flange to form a second, depending flange to conform to the insole rib. Of these three alternatives the third is decidedly the better because with it, the counter can be sewn to the insole thereby effecting a more rigid connection between the heel and forward portions of the shoe, and preventing the forward corners of the counter from creeping as they would be prone to do if the heel seat flange were merely cut away.

Forming the heel seat flange has been accomplished with entire success by the above described method, but it is extremely difficult to form the dependent shank flange, described as preferable for long shank counters used in a welt sewn shoe. It can be accomplished manually, but to do so is unsatisfactory not only because it requires an additional operation, but also because the toughness of the counter material virtually requires mechanical wiping for it satisfactorily and uniformly to retain its molded shape. Heretofore how-

2

ever, no mechanical device has been successful in accomplishing this end under satisfactory commercial conditions.

The device of my invention solves this problem and makes available for the first time a commercially feasible machine capable of simultaneously molding the flat heel seat flange and the depending shank flange of a long shank counter.

My invention is herein shown as embodied in an automatic counter molding machine of the type disclosed in my U. S. Patent No. 2,085,731, in which the heel seat flange wiper plate is mounted on a vertically sliding carrier. On this carrier and immediately below the heel flange wiper plate, is placed a pair of shank flange wiper plates mounted to slide transversely with relation to the heel flange wiper plate, and cams are provided to drive these shank flange wiper plates inwardly on the working stroke of the carrier. At the end of the working stroke of the carrier, these movable wiper plates come flush up against an upstanding plug on the face of the center mold and form the depending shank flanges.

An important feature of my invention is the angle of relative movement between the movable wiper plates and the plug against which the shank flanges are pressed. Inasmuch as the marginal portion of the counter blank must be bent flat at the tip of the center mold, and then again bent back to form the depending shank flange, if the wiper plates approached the plug at right angles, the first angle would be properly molded, but due to a stretching tension of the counter caused by its being held firm at the lip and being wiped toward the upstanding plug, when the wiper plate is withdrawn, a concise and permanent angle will not be molded into the shank flange. On the other hand, the shank flange wiper plates of my invention wipe along the upstanding plug, starting close to it and gradually pressing against it until full pressure is attained at the end of the working stroke. In this way, the stretching of the blank caused by the wiper, is largely longitudinal and when the wiper is withdrawn the blank does not recede from the upstanding plug, but rather adheres closely to it and leaves a well-formed angle.

Another advantage of my invention is the ease with which variations in shank flange size can be accomplished. This is important because often it will be desirable to change the exact location of the shank flange without otherwise changing the shape of the counter. To accomplish this, I provide plugs of various sizes to be attached to the center mold, and compensate for changes in

length by varying the effective length of the carrier's working stroke.

These and other objects and features of my invention will be more readily understood and appreciated from the following detailed description of a preferred embodiment thereof, selected for purposes of illustration and shown in the accompanying drawings in which:

Fig. 1 is a view in front elevation of the machine with molds and flange wiper plates shown as retracted prior to insertion of the counter blank,

Fig. 2 is a view in rear elevation of the carrier showing the flange plates,

Fig. 3 is a view in cross section from the left of the carrier and flange wiper plates along the line 3—3 of Fig. 2,

Fig. 4 is a plan view in cross section of the carrier along the lines 4—4 of Fig. 2,

Fig. 5 is a view in rear elevation of the right hand shank flange plate cam,

Fig. 6 is a view in side elevation of the cam shown in Fig. 5,

Fig. 7 is a view in front elevation showing the molds engaged and the carrier at the full extremity of its working stroke,

Fig. 8 is a view in front elevation of the center mold,

Fig. 9 is a view in side elevation of the center mold,

Fig. 10 is a view in side elevation of the molded counter showing the shank flange,

Fig. 11 is a plan view of the counter shown in Fig. 10,

Fig. 12 is a view in front elevation of the carrier as constructed to mold long shank counters to be used in women's high heeled shoes, and

Fig. 13 is a view in side elevation showing the carrier of Fig. 12 in pressing relation to a center mold designed to mold counters for women's high heeled shoes.

Before proceeding to the detailed description of my invention, it will be convenient first to outline its general construction and manner of operation. A pair of concave side molds 13 is mounted for limited vertical movement in the upper part of the frame, each mold being engaged to swing toward the other from the open position. Directly beneath the side molds 13 a center mold 14, resembling the heel and shank portion of a shoe last, is mounted for vertical movement on the short arm of a pendant pressure lever 23. To operate the machine, the operator inserts a counter blank between the side molds and center mold 14 and actuates the pressure lever 23. Thereupon the center mold 14 is raised against the side molds 13 causing them to swing together, taking up their limited vertical motion and applying a preliminary molding pressure to the blank. At this stage the operator may still make any necessary adjustment in the blank's position after which the final molding pressure is applied. At the time of applying the final molding pressure, a carrier 15 sliding vertically across the face of the molds operates by means of a wiper plate 25 to wipe the protruding margin portions of the counter blank inwardly and across the face of the center mold 14 to form a heel seat flange. Also during the working stroke of the carrier 15, two side wiper plates 27 are driven toward the center mold 14 by cams 28 and at the end of the working stroke they come snugly up against a shank plug plate 17 on the center mold 14, thus the flanges are formed and a finished molded counter as shown for example in Figs. 10 and 11 is the result.

Passing now to a detailed description of the preferred embodiment of my invention, it comprises an upright frame 10 which includes spaced side members joined by a heavy base plate (not shown). A cross girt 11 is secured to the upper portion of the frame by heavy bolts and is tied to the upper portion of the frame for additional support by tie rods 12.

The center mold 14 is mounted mid-way between the cross girt 11 and within the frame 10 upon a base 21. The base 21 fits in ways bolted to the upper face of a bed piece 22, which in turn is mounted on the short arm of the pendant pressure lever 23. The pressure lever 23 is pivotally mounted on a shaft (not shown) supported by the frame 10, and when rocked by means not shown, the lever arm 23 imparts vertical motion to the bed piece 22. A pair of brackets 29 are also bolted to the upper face of the bed piece 22 each of which carries in an oblique plunger 30 backed by a heavy compression spring 31 and an adjusting screw 32. Each plunger 30 carries at its upper end a contact piece 33. Thus when the pressure lever 23 raises the bed piece 22, the center mold 14 and the plungers 30 are raised and come into contact with the side molds as will be described presently.

The concave side molds 13 are suspended above the center mold 14 being joined centrally in hinged relation by the pin 19 and being suspended in place laterally by a pair of inclined toggle links 18. The links 18 have spherical ends which fit into corresponding sockets formed in the cross girt 11 and the molds 13 respectively, thus holding the side molds centrally beneath the cross girt 11. Each of the links 18 is engaged by the upper end of an oblique adjusting screw 20 by which the molds may be adjusted and properly centered with reference to the center mold 14. When the bed piece 22 is elevated by operation of the pressure lever 23, the center mold 14 carries the side molds 13 bodily upward and also swings them inwardly about the pin 19 by action of the toggle links 18, thus bringing about a preliminary engagement of the counter blank as already described. In order to apply the final molding pressure, the pressure lever 23 further raises the bed piece 22, whereupon the contact pieces 33 of the oblique plungers 30 engage an inclined face at the lower end of each side mold 13. Thus the final molding pressure is imparted to the molds through the combined action of the toggle links 18 and the plungers 30.

The mechanism for wiping the flat heel seat flange and depending blank shank flanges will now be explained. A flange plate carrier 15 is mounted to slide vertically along the face of the molds 13 and 14 in the ways 16 secured to the face of the cross girt 11. The carrier 15 is reciprocated in the ways 16 through the medium of an adjustable link 24 which is pivotally connected to the front of the carrier 15 and is driven by means not shown. On the rear face of the carrier 15, that is, the face next to the molds, a heel-seat flange wiper plate 25 is secured by machine screws. Below and on each side of the plate 25, two shank flange wiper plates 27 are mounted on cams 28 by means of positioning dowels 34 and machine screws 36. Each cam 28 comprises a cylindrical shaft 38, a narrow, rectangular plug 40 extending along the shaft 38, and an oblique head 41, and is mounted to slide transversely in the base of the carrier 15 in a corresponding

keyhole-shaped socket. The rectangular plug 40 faces rearwardly and receives a positioning dowel 34 and a machine screw 36 which secure the shank flange wiper plate 27 to it. The cams 28 are supported at their outer ends by guide rods 42 which are threaded at one end and fit rigidly into sockets in the carrier 15. At their outer end the guide rods 42 are provided with a nut head 43. The cams 28 are provided with upstanding ears 44 drilled centrally to receive the guide rods 42. A compression spring 45 is located in the keyhole shaped groove between the right and left hand cam shafts 38 and holds the cams and shank flange wipers outwardly in restrained relation against the guide rod nut heads 43.

The shank flange wipers 27 are forced inwardly during the working stroke of the carrier 15 by oblique guides 46 which are located on the lower face of the ways 16, and positioned to engage the oblique cam heads 41 when the carrier 15 is started on its working stroke. The oblique guides 46 are provided with elongated slots 47 through which the machine screws pass to hold the guides 46 in place. The elongated slots 47 are used in adjusting the slant angle of the oblique guides.

An upstanding plug plate 17 is secured to the center mold by machine screws on the face of the center mold in the shank area. The plug plate 17 is formed in the shape of a keystone with straight side edges converging downwardly. It can be readily interchanged with other plugs when changes of length or position of the shank flanges are desired.

It is important to note at this point the relationship between the slant angle of the side edges of the plug plate 17, the leading edges of the shank flange wiper plates 27, and the oblique guides 46. During the working stroke of the carrier 15 the leading edges of the wiper plates 27 are continuously parallel to the side edges respectively of the plug plate 17. However, the guides 46 are positioned at a slightly greater angle away from the vertical, and the distance between the low end of the guides 46 and the edges of the plug plate 17 is adjusted to be equal to the distance between the oblique cam heads 41, and the leading edge of the wiper plates 27 so that at the end of the working stroke, the wiper plates 27 come snugly up against the plate 17. Thus, as the wiper plates 27 approach the plug plate 17, their leading corners pass closely to the upper corners of the plug plate 17, and then as the wiper plates 27 near the end of the stroke, remaining disposed continuously in parallel relation to the plug plate 17, they gradually move closer to it, and finally lodge firmly against it.

The shank flange wiper plates 27 are provided at their upper ends with an inwardly extending ear 48. This ear 48 serves the purpose of wiping that part of the heel seat flange which lies adjacent to the shank flange. Furthermore, by wiping this part of the heel seat flange with a transverse motion, the bunching of the counter material is obviated, a bunching which would occur if the heel seat flange plate 25 were brought down flush against the top of the plug plate 17.

As can be seen from Figs. 12-13, the device of my invention can readily be adapted for molding shank flanges in long counters for women's high heeled shoes. A preferred embodiment constructed for this purpose comprises a carrier 52 carrying a pivotally mounted end piece 53 held in restrained relation and always urged towards the molds by cooperating compression springs 54 and 55. By reference to Fig. 13 it can be seen

that the end piece 53 is pivotally mounted on the pin 57 connecting it to the rocker arms 56; and also the end piece 53 is pivotally mounted on a second pin 58 connecting it to the spring tension link 60. At its other end the spring tension link 60 passes through a hole provided for it in a raised part of the body of the carrier 52. The rocker arms 56 are pivotally mounted centrally on a pin 61 which is supported by the carrier 52. Two compression springs 54, one connected to each rocker arm at the other end thereof interconnect the said arms to the carrier 52. The end piece 53 has a curved rear surface conforming to the face of the high heel counter molds, and it supports similarly curved shank wiper plates 62. These wiper plates 62 are supported on cams 63 which slide transversely in a key-hole groove in the end piece 53 and the cams 63 engage oblique guides 64 essentially in the same manner as described above for men's shoe counters. However, the guide rods 65 which retain the cams 63 are located below the cams 63; rather than above.

The operation of this latter embodiment, constructed for women's shoe counters, is slightly different in one respect from the operation of the first described embodiment. At the bottom of the working stroke, the end piece 53 exerts considerable molding pressure on the counter as well as performing the flange wiping function. This pressure is applied by the driving link 24, but in order to compensate for slight variations, the springs 54 and 55 allow the end piece 53 to recede and pivot to a limited extent.

While this and other variations will be apparent to those skilled in the art, the invention is not limited to the precise embodiment shown herein, but is rather to be measured by the terms of the appended claims.

Having thus described my invention what I claim as new and desire to secure by Letters Patent of the United States is:

1. A machine for molding counters, comprising side molds and a center mold for shaping the body of a counter blank, a reciprocating carrier having a fixed wiper plate mounted therein so constructed and arranged as to pass in close relation to the said molds on the working stroke of the carrier and to depress the edge of the counter blank to form a flat heel seat flange, an upstanding shank flange mold on the face of the said center mold, and lateral wiper plates reciprocating simultaneously with the said carrier, adapted to wipe a flat heel seat flange at the side of the heel portion of the counter blank, to converge upon the shank portion of the counter blank, and pressing it against the said shank flange mold to form depending shank flanges.

2. A counter molding machine comprising side and center molds for engaging a counter blank, a plug plate secured to the said center mold, fixed guides adjacent to the said molds, flange plates movable in said guides so constructed and arranged as to wipe a flat heel-seat flange at the heel portion of the counter and to press the forward corners of the counter against the said plug plate to form depending shank flanges, and means for reciprocating the flange plates in the said guides.

3. A counter molding machine comprising side and center molds for engaging a counter blank, a plug plate secured to the said center mold in the shank area, a multiplicity of fixed guides adjacent to the said molds, a flange plate movable in one pair of said guides for engaging the

heel portion of the counter blank, flange plates movable in other pairs of guides adapted to wipe the margin of the counter blank flat at the sides of the heel area and to press the said margin against the said plug plate, and means for reciprocating the flange plates in the said guides.

4. A counter molding machine comprising a center mold resembling in shape the heel and shank portions of a shoe last, a plug plate conforming to the sole surface of the center mold and secured to it on the bottom of the shank, side molds, fixed guides adjacent to the said molds, a carrier movable in said guides, means for reciprocating the said carrier in the guides, a fixed wiper plate mounted on the said carrier and so constructed and arranged as to engage the marginal edge of the heel portion of the counter blank during the working stroke of the said carrier, movable wiper plates mounted on the said carrier to slide transversely with relation to the said fixed wiper plate and to engage first the marginal edges of the heel portion of the counter blank at the sides thereof and then the shank portion thereof during the working stroke of the said carrier, cams secured to the movable wiper plates, fixed oblique guides adjacent to the molds so constructed and arranged as to engage the said cams, during the working stroke of the said carrier, and to cause the said movable wiper plates to converge against the said plug plate.

5. A machine for molding counters, comprising a plug conforming to the shape of the heel and shank portions of a shoe last, walls in the shank portion of the said plug running longitudinally along the plug and depending perpendicularly from the sole level, side molds conforming conversely to the said plug and operatively associated with the said plug for the purpose of molding the body of a counter blank, mechanism for wiping the marginal edges of the counter blank to form a flat heel seat flange and depending shank flanges comprising the following, viz: guides adjacent to the said molds, a carrier mounted for reciprocation in the said guides, a fixed wiper plate mounted on the said carrier and so constructed and arranged as to engage the

heel portion of the counter blank during the working stroke of the said carrier, movable wiper plates mounted on the said carrier to slide transversely with relation to the said fixed wiper plate and to engage first the side margins of the heel portion of said blank, wiping them flat and then engaging the shank portion of the counter blank to compress it against the said walls at the end of the working stroke of the said carrier, cams secured to the movable wiper plates, fixed oblique guides adjacent to the molds so constructed and arranged as to engage the said cam, during the working stroke of the said carrier, and to cause the said movable wiper plates to converge against the said plug plate.

6. A counter molding machine as described in claim 5 further characterized by the fixed oblique guides having only a slightly greater oblique angle than the said walls in the shank portion of the plug, such that as the leading corners of the movable wiper plates approach the said walls the shank portion of the plug, they pass close to the rear corner of the said walls and thereafter longitudinal and only slightly transverse.

7. A machine for molding counters comprising side and center molds for shaping the body of a counter blank, a flat plug secured to the center mold at the shank portion thereof having obliquely aligned side walls converging toward the shank end of the said center mold, side flange plates constructed and arranged to move in convergent paths substantially at the same angle of convergence as the walls of the said flat plug and to exert firm pressure against the said walls at the end of a working stroke.
